(57) **CLAIM**

The ornamental design for a garden lamp, as shown and described.

DESCRIPTION

FIG. 1 is a perspective view including a front, left and top side of a garden lamp showing my new design;

FIG. 2 is a perspective view including a rear, right and bottom side of the garden lamp;

FIG. 3 is a left side elevation view of the garden lamp;

FIG. 4 is a right side elevation view of the garden lamp;

FIG. 5 is a front elevation view of the garden lamp;

FIG. 6 is a rear elevation view of the garden lamp;

FIG. 7 is a top plan view of the garden lamp;

FIG. 8 is a bottom plan view of the garden lamp;

FIG. 9 is an enlarged detail view of the encircled portion of FIG. 1; and,

FIG. 10 is an enlarged detail view of the encircled portion of FIG. 2.

The dot-dash broken lines in FIGS. 1, 2, 9 and 10 delineate a portion of the claimed design that is shown on an enlarged scale in FIGS. 9 and 10. The portions of the Figures shown in phantom lines are for illustrative purpose only and form no part of the claimed design.
